Fig. 4

FIG. 1 is a top plan view of a desk name plate showing my new design;

FIG. 2 is a front elevational view;

FIG. 3 is a rear elevational view; and

FIG. 4 is an end view thereof.

The characteristic feature of my design resides in the combination of an elongated base member of semi-circular cross-sectional shape and having a flat underside adapted to rest flat on a horizontal supporting surface, such as a desk top, and having an arcuate viewable surface simulative of the bark of a log and having opposing beveled ends with annular pegs upstanding from the arcuate surface substantially centrally thereof and spaced apart along the longitudinal axis of the base member, said pegs having axial coplanar slots to evenly receive and support the side edge of a flat substantially rectangular plate having rounded corners and having a flat face portion on which a rectangular name plate is releasably fixedly superimposed, all as shown.

I claim:

The ornamental design for a desk name plate, as shown and described.
